UNITED STATES PATENT OFFICE.

THOMAS H. DODGE, OF WORCESTER, MASSACHUSETTS.

COTTON-BALE TIE.

SPECIFICATION forming part of Letters Patent No. 280,725, dated July 3, 1883.

Application filed April 21, 1883. (No model.)

To all whom it may concern:

Be it known that I, THOS. H. DODGE, of the city and county of Worcester, and Commonwealth of Massachusetts, have invented 5 certain new and useful Improvements in Cotton-Bale Ties; and I do hereby declare that the following is a full, clear, and exact description of the same, reference being had to the accompanying drawings, forming a part of 10 this specification, in which—

Figure 1 represents a side view of a cotton-bale tie having my said improvements added thereto. Fig. 2 represents a perspective view of the same tie when united or connected to the loop ends of the band. Fig. 3 represents a cross-section on line *a b*, Fig. 1; and Figs. 4, 5, 6, and 7 represent modifications, as will be hereinafter more fully described.

20 To enable those skilled in the art to which my invention belongs to make and use the same, I will proceed to describe the device more in detail.

My invention consists of improvements in 25 the cotton-bale tie patented to J. J. McComb, January 29, 1861, as will be hereinafter more fully described.

In the drawings, the part marked A is the 30 complete tie, and embraces the said Mc- Comb's invention, in combination with which certain new elements are formed, viz:

First. A strengthening-groove, *c'*, on both sides, and which enables the device to be made lighter, while at the same time additional 35 strength is obtained. The groove *c'* prevents the ends B and C from bending or springing out, and consequently a thinner piece of metal can be employed than as made prior to my invention.

40 Second. In the McComb tie, as patented, the square corners were left at the points *d'*, and the tie was liable to break at one of those corners, but which difficulty has been overcome by making the cut slightly rounding, as shown in the drawings, and this also permits a thinner plate to be used.

Third. As the original tie was made the inner corners, *f*, were square, and consequently when the band D was strained on 45 these sharp edges the band was not only liable to be cut, but the separate tie ends B and C were liable to be twisted by the sharp edges thereof, preventing any slip of the loop when subjected to great strain as the bale

left the compress, and this twisting action 55 tended to wrench such ends off at the inner corners, *d' d'*. This I obviate by constructing the tie with rounded inner edges, *f f*.

If preferred, the tie may be made long, 60 enough to give sufficient strength of metal at the ends *g g*, without the groove extending entirely around the opening F, in which case the groove may extend only on one side, as indicated in Fig. 4, or at the corners, as shown in Fig. 5, Fig. 6 representing a section on line *c d*, Fig. 4, and Fig. 7 a section on line *e*, Fig. 5, of the drawings.

In the drawings the slit for the introduction of the band is indicated by the figure 8. The long grooves upon the side of the tie 70 through which the slit 8 is made are formed by means of rolls, at the same time the strip itself is rolled out, and the shape given by the grooves imparts great stiffness to that part of the tie-piece which is weakened by the 75 presence of the slit, while the swaging or compression of the metal between the rolls itself increases the strength of the piece. The smaller grooves may be formed either by compression-dies or by rolls provided with 80 projections of the proper shape. By this formation a much stronger tie-piece is obtained with the same or a less weight of metal.

The edges *f f* may be milled off or pressed round, and such operation be performed at 85 the time of cutting or stamping out the opening F.

Having described my improvements in cotton-bale ties, what I claim therein as new and of my invention, and desire to secure by Letters Patent, is—

1. A metal strip for a cotton-bale tie, provided with a central opening, and having strengthening-grooves formed by compressing the metal, substantially as described.

2. A bale-tie provided with a central opening having rounded corners and edges, and with strengthening-grooves around the sides of said opening, substantially as described.

3. A metal strip for making cotton-bale 100 ties, provided with corrugations *c'* along the edge, through which the slits 8 are made, substantially as set forth.

THOMAS H. DODGE.
